UNITED STATES PATENT OFFICE.

ARTHUR J. THIBODEAUX, OF CHICAGO, ILLINOIS, ASSIGNOR OF ONE-HALF TO JOHN W. KRAMER, OF CHICAGO, ILLINOIS.

TISSUE-HOLDER FOR MANUFACTURING MATRIX-MATS.

1,272,572.

Specification of Letters Patent. Patented July 16, 1918.

Application filed April 9, 1917. Serial No. 160,881.

To all whom it may concern:

Be it known that I, ARTHUR J. THIBODEAUX, a citizen of the United States, and a resident of Chicago, in the county of Cook and State of Illinois, have invented certain new and useful Improvements in Tissue-Holders for Manufacturing Matrix-Mats; and I do hereby declare that the following is a full, clear, and exact description thereof, reference being had to the accompanying drawings, and to the characters of reference marked thereon, which form a part of this specification.

This invention relates to an improved tissue sheet holder for use in the manufacture of mats from which matrices are made in which to mold stereotypes, and the purpose of the invention is to provide a tissue holder or shelf having means to adjustably support the same on a support with respect to the table on which the sheets of tissue paper are assembled when producing the mat, the adjusting means permitting the shelf to be adjusted in one or more ways to properly position the sheet with respect to the assembling table, together with means for locking the shelf or holding member in adjusted positions.

The invention also contemplates an arrangement of the support for the tissue holding member or shelf such as will enable the shelf to swing on its support at its front end toward and from the assembling table, and to means for adjustably locking the shelf at any desired angle relatively to the plane of said table. The said angle restricting means may also be constructed so as to give the shelf some freedom of movement which will permit the front end of the shelf to swing downwardly toward the table under the pulling stress of a sheet of tissue when drawn off the shelf on to the assembling table, and the shelf may be slightly over-weighted at its rear end, so that when the pulling stress is released the front edge of the shelf may automatically rise to give ample clearance space between the same and the assembling table.

The invention also contemplates novel sheet gripping or confining means at the front edge of the shelf between which the

front edges of a group of tissue sheets are clamped or confined; said clamping means being preferably associated with pins which pierce the front edges of the sheets to hold them properly assembled.

The invention also contemplates other improvements in devices of this character which look toward the simplifying and convenience of the device in use, and the invention consists in the combination and arrangement of the parts shown in the drawings and described in the specification, and is pointed out in the appended claims.

In the drawings:—

Figure 1 is a side elevation of a tissue assembling table equipped with a tissue holder embodying my invention.

Fig. 2 is a plan view thereof.

Fig. 3 is an enlarged side elevation of the tissue holder shelf and supporting devices therefor.

Fig. 4 is a cross section on the line 4—4 of Fig. 3.

Fig. 5 is a longitudinal section on the line 5—5 of Fig. 4.

As shown in the drawings, 10 designates the assembling table having a mat assembling area on which the tissue sheets are assembled to produce the mats. 11 designates the tissue-holding member or shelf that is sustained in rear of said mat assembling area on a suitable up-standing support comprising a horizontal member 12 and end members 13 which rest on the table or a part stationary therewith. The tissue holding shelf 11 may be made of a single piece of wood or like material.

The tissue supporting shelf is pivotally supported between its ends on a horizontal rod or shaft 15 which extends transversely across the rear end of the assembling table, and said shaft is supported at its ends in carrying members 16 that extend between and through guide openings in, upturned arms 17, 18 of brackets 19 that are attached to the member 12 of the upstanding support. The direct connection between said shelf 11 and the shaft 15 comprises apertured ears 20 that are attached to the shelf 11 and are bent downwardly from the plane thereof. The shaft 15 is held from endwise

displacement by nuts 21 screw threaded to the ends of the shaft.

The shaft carrying members 16 are connected to adjusting means for adjusting the position of the shelf in a direction from front to rear of the assembling table. The particular adjusting means herein shown is made as follows:

The front arms 17 of the leaf supporting brackets are extended upwardly alongside the side edges of the shelf and are apertured to receive adjusting screws 23 which have swiveling engagement at their rear ends with lugs 24 that are attached to and rise from the carrying members 16. Said screws are provided with any suitable form of hand pieces 25. By turning said screws equally in their bearings and, in the same direction, the said sliding carrying members 16 are shifted endwise in their guides in the upstanding arms 17 and 18 in a direction, depending on the direction of the rotation of the adjusting screws, and said carrying members carry along with them the shaft 15 and the shelf supported thereby. These devices enable the shelf to be adjusted toward and from the assembling table and locked in position.

In addition to said fore-and-aft adjustment, means are provided for adjusting the shelf laterally with respect to said assembling table. The latter adjustment is effected in the present instance by means of an adjusting screw 28 which extends through 35 and is threaded in an aperture in one of the carrying members 16 and the inner end of the said adjusting screw has a swiveled connection with a downturned lug 29 attached to the adjacent edge of said shelf. 40 A single adjusting screw is all that is required to effect such lateral adjustment of the leaf, the leaf being guided in its lateral movement by the apertured lugs 20 which engage the supporting shaft 15.

Means are provided for adjusting the angle of the tissue supporting shelf with respect to the horizontal. Said means consist, as herein shown, of front and rear, upright adjusting screws 30, 31, respectively, which extend through and are threaded in apertures in a plate 32 that is fixed centrally of the device to the lower side of the supporting member 12, and said screws bear at their upper ends against wear plates 33, 34 applied to the lower face of the tissue supported shelf. By releasing one of the adjusting screws 30 and turning the other adjusting screw 31 toward the shelf, or vice versa, the angle of the shelf to the horizontal may be varied as desired.

If desired the rear end of the shelf may be overweighted with respect to that portion of the shelf in front of the pivot shaft 15 and the adjusting screws 30, 31 may be so adjusted that the overweight of the rear

end of the shelf tends to hold the said shelf in a rearward and downwardly inclined position, and with the front edge thereof raised away from the assembling table. When the device is thus used the rear adjusting screw 31 will be backed off from the shelf to permit the rear end of the shelf to drop downwardly beyond the horizontal when the movement of said shelf is otherwise unrestrained.

At the front end of the shelf is provided clamping means for clamping the forward edge to a group of sheets S supported on the shelf. The clamping means comprise upper and lower clamping bars 35, 36, respectively, the latter lying on the upper face of the shelf at the front edge thereof. 37, 37 designate sharpened pins which are anchored in and extend upwardly from the front corners of the leaf and said pins extend through apertures in the ends of the upper and lower clamping bars, the upper bar being adapted to slide on said pins. The pins are adapted to pierce the front edge of the group of sheets. Pressure means are provided, in association with the upper clamping bar tending to press the same toward and against the bundle of sheets, and said pressure means are adjustable to cause the upper clamping bar to follow the decreasing thickness of the sheet group as the sheets are withdrawn therefrom.

Said pressure means comprise in the present instance clamping brackets 38, 38, one at each side of the leaf, having internal ends 39 which fit over the ends of the upper clamping bar and are apertured to receive the pins 37. The brackets are formed at their lower ends with out-turned arms 40 which are apertured to receive upright posts 41, which may be made integral parts of the adjacent pins 37, in the manner indicated in Fig. 4. Between said out-turned arms 40 and nuts 42 threaded to the ends 100 of the posts 41 are interposed suitable expansion springs 43. Said springs serve to yieldingly force the upper clamping bar 35 against the group of sheets, and the screw threaded nuts 42 enable the pressure applied to the upper clamping bar to be varied and to adjust the upper clamping bar to correspond with the thickness of the groups of sheets confined thereby.

One use of the device is indicated in Figs. 120 1 and 2. In making up a mat, after the foundation layer m thereof has been laid upon the assembling table and paste applied to the upper face thereof, the uppermost tissue sheet of the group of the shelf 11 is 125 drawn forwardly over the assembling table in the manner indicated in Fig. 1 and the forwardmost edge is adhered to the mat foundation sheet m. In this position the sheet is connected to the shelf by reason of 130

the passage of the pins 37 through the edge of the sheet. A roller 45 by which the tissue sheet is laid smoothly and uniformly upon the pasted sheet *m* is then rolled rearwardly over the tissue sheet and applies or lays the tissue sheet on the foundation sheet, and the pulling tension effected by the rolling of the sheet tissue on the assembling mat eventually tears the applied sheet from the pins 37, whereby the tissue sheet may be applied to the foundation sheet throughout the entire length of the foundation sheet. If the tissue supporting shelf be delicately balanced by means normally tending to rearwardly overbalance the same, the tension pull exerted on the forward end of the shelf when the tissue sheet is thus applied will serve to swing the forward end of the shelf downwardly and after the sheet has been parted therefrom the overweight of the rear end of the leaf will swing the forward end of the shelf upwardly.

It is to be understood that the structural details of the invention may be varied within the spirit and scope of the invention, and the invention, therefore, is not limited to such detail except as to claims wherein the same are specifically set forth, and are imposed by the prior art.

30 I claim as my invention:—

1. The combination with a stationary table having a mat assembling area, of a tissue supporting device comprising a shelf located in rear of and above the level of the table to receive and support a group of tissue sheets, tissue sheet retaining means at one margin of the shelf, a support for said shelf and means for adjusting said shelf on said support relatively to said assembling area.

2. The combination with a table having a fixed mat assembling area, of a tissue supporting device comprising a shelf located in rear, and above the level, of said area to receive and support a group of tissue sheets, a support for said shelf and separate means to effect lateral and fore-and-aft adjustments of the shelf relatively to said assembling area and to lock it in adjusted positions.

3. The combination with a fixed table having a mat assembling area, of a tissue supporting device comprising a fixed support, a shelf above the level of the table and in rear of said assembling area to receive and support a group of tissue sheets, and provided with sheet retaining means, and means to hinge said shelf to said support to permit it to swing toward and from said assembling area.

4. The combination with a mat supporting table, of a tissue supporting device comprising a fixed support and a shelf above the level, and at the rear, of the table to receive and support a group of tissue sheets

and having means to hinge it to said support to swing toward and from the table, with means to adjustably lock the shelf in different angles relatively to the horizontal plane of the table.

5. The combination with an assembling table, of a tissue supporting device comprising a fixed support, a shelf above the level, and at the rear, of the table, adapted to receive and support a group of tissue sheets, a shaft extending across said support to which said leaf is hinged to swing vertically and means to adjust the shelf longitudinally of said shaft and to lock it in adjusted positions.

6. The combination with an assembling table, of a tissue supporting device comprising a fixed support, a shelf above the level, and at the rear, of the table, adapted to receive and support a group of tissue sheets, a shaft extending across said support to which said leaf is hinged to swing relatively and means to adjust the shelf longitudinally of said shaft, with other means to adjust said shaft toward and from the assembling table.

7. In combination, a mat supporting table, a tissue supporting shelf above and in rear of the assembling area of said table with means at the forward edge of the shelf to retain a group of tissue sheets which are supported on the shelf and over which the sheets are severally turned to transfer them to said assembling area, and means to adjust said shelf relatively to said table.

8. In combination, a mat supporting table, a tissue supporting shelf above and in rear of the assembling area of said table with means at the forward edge of the shelf to retain a group of tissue sheets which are supported on the shelf and over which the sheets are severally turned to transfer them to said assembling area, and separate means to independently adjust said table both vertically and laterally relatively to said support.

9. In combination, a mat supporting table, a tissue supporting shelf above and in rear of the assembling area of the table, with means at the forward edge of the shelf to retain a group of tissue sheets, and pivot means for supporting said shelf, constructed to permit the forward end of the shelf to rise and fall relatively to the mat assembling area of the table.

10. In combination, a mat supporting table, a tissue supporting shelf above and in rear of the assembling area of the table, with means at the forward edge of the shelf to retain a group of tissue sheets, and pivot means for supporting said shelf, constructed to permit the forward end of the shelf to rise and fall relatively to the mat assembling area of the table, with means to control the pivoting movements of said table.

11. A tissue supporting device comprising fixed supports, a shelf to receive and support a group of sheets, a shaft extending across the supports to which the shelf is pivoted, members slideable on said supports in which the said shaft is sustained, and means for adjusting said members forwardly and rearwardly and for locking them in adjusted positions.
- 10 12. A tissue supporting device comprising fixed supports, a shelf to receive and support a group of sheets, a shaft extending across the supports to which the shelf is pivoted, members slideable on said supports in which the said shaft is sustained, and adjustable means acting on the shelf to shift said shelf endwise of said shaft and laterally with respect to the supports.
13. In a tissue supporting device a shelf provided at its forward edge with upper and lower clamping bars, pins extending through apertures in said bars and adapted to pierce a group of sheets confined between

the bars and adjustable and yielding means to press said bars together.

14. In a tissue supporting device, a shelf provided at its forward edge with upper and lower clamping bars, pins extending through apertures in said bars and adapted to pierce a group of sheets confined between the bars, 30 clamping brackets applied over the upper clamping bar, posts attached to the shelf with which said brackets have sliding engagement, nuts threaded to said posts and springs interposed between said nuts and 35 brackets.

In witness whereof I claim the foregoing as my invention, I hereunto append my signature, in the presence of two witnesses, at Chicago, Illinois, this 31st day of March, 1917.

ARTHUR J. THIBODEAUX.
